BENJAMIN P. FORTIN, OF HARTFORD, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,212,756.

Specification of Letters Patent. Patented Jan. 16, 1917.

Application filed September 15, 1915. Serial No. 50,765.

To all whom it may concern:

Be it known that I, BENJAMIN P. FORTIN, a citizen of the United States, residing in Hartford, in the county of Hartford and State of Connecticut, have invented certain new and useful Improvements in Type-Writing Machines, of which the following is a specification.

This invention relates principally to type-writing machines, and more especially to machines of the general character shown in the patent to Wernery and Smith, No. 1,132,055. Such machine is adapted for writing on a number of superposed webs or continuous sheets, especially those folded longitudinally and intended to be torn off in cross-sections from the body of the web, as for example when the web comprises a series of printed forms. In such work it is usual to employ ink-ribbons or carbon sheets interleaved with the webs for making duplicate copies. After a section of web has been written the platen is shifted away from the usual feed-rollers to release the web and the interleaved carbon sheets, whereupon, by means of a carrier or holder the carbon sheets are drawn back along the web preparatory to printing on the succeeding section of the web. The same carbon sheets are thus used repeatedly with the same web. The carbon sheet holder of a machine of this character is usually supported on a carriage which rides on a track provided on a frame or table attached to the platen carriage. Said table and carbon sheet holder therefore partake of the letter-feed and return movements of the platen carriage, while the carbon-sheet holder has also its own line-spacing and return movements on the table, but toward and away from the platen.

An object of the present invention is to provide a practical form of carbon-sheet carriage, supporting table, and tracks for the carriage whereon the carriage shall be accurately guided without undue lost motion, and at the same time without binding of the carriage on the track, and to further combine these features in a construction which can be made cheaply and of inexpensive material.

A further object of the invention is to provide a construction wherein the track rails are made separately from the table, are of simple form, readily constructed with

their guiding edges true, and which are easily attachable in true position on the table.

In the preferred embodiment of the invention the table is conveniently and cheaply made with great strength and lightness, of tubing or the like, bent or put together in the form of a rectangular skeleton frame. The use of tubing for the framework gives lightness combined with great rigidity. While tubing might also serve as a track for the carriage, still, owing to the fact that it may be more or less irregular in form and present difficulties in bringing the sides of the frame into exact parallelism, for accurately guiding the carriage, I prefer to make the guide rails of separate flat strips of metal which may be readily machined to make their guiding edges straight and true. The rails further add to the strength and stiffness of the frame, and the form of their guiding edges is better suited than the round surface of the tubing, for holding the carriage rollers and preventing vertical displacement of the carriage. The rails are set on the skeleton frame in tested position and then secured by screws, or otherwise, to the frame. The carriage for the carbon-sheet holder preferably comprises two trucks, one at each side thereof, each provided with a grooved roller journaled in the truck for rotation about an axis perpendicular to the plane of the track and engaging one edge of a rail, so that the rollers of one truck prevent lateral displacement of the carriage in one direction, and the rollers of the other truck prevent lateral displacement in the opposite direction. The carriage is thus accurately guided so that the carbon sheets, as well as the webs or work-forms, which are also guided over the carbon-sheet carriage, are caused to run true, and are accurately fed to the platen in a direction normal thereto. The rollers may be located on the under side of the trucks, the latter being provided with depending guards which extend beneath the rollers to provide journal bearings therefor. Said trucks may also be provided with guards depending therefrom opposite the rollers, so that each guide-rail or track-rail extends between the rollers of one truck and the guards opposite said rollers.

Other features and advantages will appear hereinafter.

In the accompanying drawings, Figure 1 is a perspective view of a construction embodying the invention as applied to an Underwood typewriting machine, the parts being in position to permit writing upon a work-piece. Fig. 2 is a sectional elevation view through the table and carbon-sheet carrier. Fig. 3 is a sectional elevation showing the platen and feed-rolls. Fig. 4 is a perspective view showing the truck on which the right-hand side of the carbon-sheet carrier is supported, and also showing a portion of the table and the rail on which said truck rides.

Referring particularly to Fig. 1, which shows the general arrangement of the platen carriage, carbon-sheet holder, and means for unfolding or straightening the web to permit the carbon sheets to be retracted; the platen 10 is fixed to a platen shaft 11 journaled in arms 14 and 15 of a frame fast to a rock shaft 12. The shaft 12 has bearings in the ends 13 of the usual platen frame. The swinging frame is normally held in the Fig. 1 position for writing, with the platen down against the front and rear feed-rolls 69, 70, Fig. 3, and may be swung from this position to its web releasing position by means of an arm 16 fast to the rock shaft 12, and provided with a handle 16^a. For locking the swinging frame in the Fig. 1 position, said arm 16 carries a pin 17 adapted to be engaged by a hook 18 pivotally mounted on the platen frame end 13. A spring 19 yieldingly holds the hook in operative position, and in returning the parts to such position, the pin 17 cams back the hook so that the locking may be automatic. A tooth 20 on the hook, together with a pin 22 on the right-hand end 13 of the platen frame, determines the return throw and normal position of the swinging frame.

The platen may be rotated by the usual hand wheel 24, or the line-space ratchet wheel 25, both fast to a short shaft 26 mounted to rotate in the left-hand end 13 of the platen frame. When the platen is in printing position the shaft 26 is in alinement with the shaft 11. As is common in Underwood typewriting machines, the ratchet wheel is actuated by a pawl 27 on the usual slide engaged by one arm of a line-space lever 29 on the carriage frame. A spring actuated detent 34 engages the ratchet wheel 25 to hold the platen against rotary displacement. The driving connection between the shaft 26, whose axis is stationary, and the platen shaft 11, which swings upward from normal position, consists of gears 35, 36 and 37. The gear 35 is fast on the shaft 26, the gear 36 is fast on the platen shaft, and of the same diameter and provided with the same number of gear teeth as the gear 35, and the gear 37 is loose on the axle 12, around which the platen swings as an axis,

said gear 37 having a face of sufficient width to mesh with both gears 35 and 36. The driving connection between the shaft 26 and the platen is thus maintained in all positions of the platen.

In the operation of removing a printed length from the webs and in readjusting the carbons for printing the next length, the platen is swung from printing position away from the feed-rolls, so that the webs and carbon sheets are no longer wrapped around the platen, and the carbon sheets may be moved freely between the webs to return them to a position opposite a succeeding portion of the webs. The webs may be formed from a single piece fan-folded longitudinally to provide for several copies when the carbon sheets are interleaved with the folds.

The webs may be fed into the machine over the rear end of a table 38, which in accordance with the present invention comprises a piece of tubing bent to form a rectangular frame, the front reach 39 of which has ears 40 attached thereto, by means of which the frame is secured to bracket arms 41 on the platen carriage. The table frame is braced by a tube 49 extending lengthwise thereof and which may form a support for the webs as they are fed over said table to the platen. A bracket 50 depending from the tube 49 carries a roll 51 which runs on a rail 52 parallel with the platen and forming part of a frame-work 53, the latter secured to the main frame of the machine, so that said frame-work supports the table at the rear end thereof. The web is led forward over the table and over a tie-rod 42 of the platen carriage, and down around the platen between the latter and the feed-rolls, up past the printing line, under the cutter 44, and onto the paper shelf 45 between the side-edge gages 46.

When measured lengths of the webs are to be severed, they may be drawn to the gage 54, carried by the bar 54^a on the paper shelf. The cutter is shown as a plate secured to the sleeve 47 on the shaft 12, to which sleeve is also secured a finger 48 for rocking the cutter into engagement with the web when the latter is to be cut. The printing on the web is effected by types 43 which may be operated by the usual mechanism.

The carbon sheets, by means of the binding action thereon of the webs, are caused to advance with the webs at each line-space rotation of the platen, and when the platen is shifted upwardly, as before noted, the carbon sheets are released and may be drawn back along the webs from the written to the next unwritten length thereof. To provide for these movements of the carbon sheets, the same, in machines of this character, are attached at their rear edges to a traveling holder or carriage. This carriage, as shown, comprises a body portion or plate 55, having

a stepped block 56 at each side thereof. Fingers or clips 57, to each of which one carbon sheet may be attached, are secured by screws 58 to the steps 59 of the blocks 56. The length of each finger is less than the width of the webs, and the fingers are placed in staggered relation, alternate fingers being secured to the same side of the carriage, so that the fingers may project into the oppositely-directed fan-folds of the webs.

The carriage body or plate 55 is mounted on trucks adapted to ride on rails at the sides of the table, and a feature of the present invention relates to the construction of these trucks. Each truck consists of a plate 60 having adjacent the outer corners thereof ears 61, on which are mounted rollers 62. Said ears comprise depending portions, the inwardly turned horizontal portions, the latter providing bearings for the vertical axles of the rollers 62 which lie horizontally and are formed with grooves 63 to engage the outer edges of guide-rails or track-rails supported on the tubular skeleton frame 38. At the inner corners of each truck plate 60 are ears or guard lugs 72 which extend down past the inner edge of the adjacent rail 64, said lugs being preferably opposite the rollers 62.

The table skeleton or frame is preferably made of tubing because it can be cheaply and easily made, and provides a light, strong and durable structure. Said frame may be made of a single piece, the ends of which are joined at one corner, or other part of the table, or it may be made of several pieces. Since the carbon-sheet carrier does not ride directly upon the table frame, no particular exactness or regularity of shape is required for the latter, and hence the frame may not only be made of tubing, but of other suitable material and form.

In the present construction provision is made for free movement of the sheet carrier and accurate guiding of the latter in its travel without undue lateral play, but such provision concerns the rails and the manner in which the trucks are mounted on the same, rather than the table frame proper as in previous constructions.

The rails 64, which are shown as two flat metal strips, may be easily made with their edges practically straight. The alinement of the rails on their supporting frame is also a simple matter. For example, one rail may be placed on the table and set to true position thereon and fastened to the table, as by the means of screws 65, with the edge of the rail perpendicular to the direction of letter-feed movement of the platen carriage. The screws 65 may extend through holes in the guide-rail, and into threaded holes drilled in the tubular frame 38. One or more of said holes in the tubular frame may be drilled after the guide rail has been alined

thereon and the position for such holes thereby determined. After one rail has thus been secured to the frame, the opposite rail may in like manner be positioned and secured in parallelism with the first rail, and at such a distance therefrom, that the rollers 62 can run freely on the rails with a minimum of lost motion or lateral play. The carriage plate 55 is secured to the truck frames as by means of screws 73. The flanges on the rollers 62 positively prevent the carriage from jumping the rails, and also prevent any material vertical play of the carriage on the rails.

Variations may be resorted to within the scope of the invention, and portions of the improvements may be used without others.

Having thus described my invention, I claim:

1. In a typewriting machine, the combination with a platen, of means for advancing material thereto, said means comprising a carriage movable toward and from the platen, a supporting frame for the carriage, guide rails, means to secure said rails in parallelism on the frame, grooved guide-rollers on the carriage arranged with their axes perpendicular to the plane of said supporting frame to run on said guide-rails, the latter arranged with their guiding edges in parallelism for the correct guidance of the carriage.

2. In a typewriting machine, the combination with a platen and a platen carriage, of means for advancing material to the platen, comprising an auxiliary carriage movable toward and from the platen, a frame on which said auxiliary carriage is mounted, said frame secured to the platen carriage to travel therewith as the platen is advanced in letter-feeding direction, said frame formed of tubular material, guide-rails on which said auxiliary carriage is guided, and means for securing said rails to the frame with their guiding edges parallel and extending perpendicular to the direction of travel of the platen carriage for guiding said auxiliary carriage.

3. In a typewriting machine, the combination with a roller platen and a platen carriage, of an auxiliary carriage for holding transfer material between the plies of a work-piece during the line-space feed of the transfer material and work-piece, and for shifting the transfer material at intervals backward along the work-piece, a supporting frame for said auxiliary carriage attached to the platen carriage and traveling therewith, and extending rearwardly therefrom, said supporting frame also forming a table over which the work-piece is guided, said auxiliary carriage comprising a body of sheet material, trucks secured to said body and carrying grooved guide-rollers arranged with their axes perpendicular to the

plane of the supporting frame, guide-rails, and means to secure the guide-rails on the supporting frame with their guiding edges parallel and perpendicular to the direction 5 of travel of the platen carriage, said rollers running on said rails to thereby guide the auxiliary carriage and hold it on the supporting frame.

4. In a typewriting machine, a carriage 10 for sheet material to be fed to the platen, said carriage comprising a horizontally disposed body of sheet material, trucks, each comprising a body of sheet material, said trucks arranged beneath the body of said 15 carriage and removably attached thereto, and rollers journaled in the said trucks, with their axes perpendicular to the body of the carriage.

5. In a typewriting machine, a carriage 20 for sheet material to be fed to the platen, said carriage comprising a horizontally disposed body of sheet material, trucks, each comprising a body of sheet material, said trucks arranged beneath the body of said 25 carriage and removably attached thereto, and rollers journaled in the said trucks, with their axes perpendicular to the body of the carriage, said trucks comprising guards depending from the outer edges thereof and 30 having inturned portions providing journal bearings for the axes of said rollers.

6. In a typewriting machine, a carriage 35 for sheet material to be fed to the platen, said carriage comprising a horizontally disposed body of sheet material, trucks, each comprising a body of sheet material, said trucks arranged beneath the body of said carriage and removably attached thereto, and rollers journaled in the said trucks, with 40 their axes perpendicular to the body of the carriage, said trucks also comprising guards depending therefrom, opposite said first-mentioned guards, and spaced from the rollers to provide a passageway for tracks or 45 guide-rails on which said rollers are adapted to run, said rollers having peripheral flanges to embrace the edge of said rails.

7. In a typewriting machine, the combination with a paper carriage, of a frame connected to the carriage to travel therewith, said frame comprising tubular side bars extending transversely to the direction of travel of the carriage, parallel flat rails mounted on said bars and extending lengthwise thereof, and a work-supporting truck 50 having rollers arranged to run on said rails, each rail having one of its longitudinal edges positioned laterally beyond the supporting bar, said rollers arranged to run on said edges and mounted for rotation about 55 axes perpendicular to the rails.

8. In a typewriting machine, a platen, a carriage therefor, a sub-carriage for holding transfer material between the plies of a work-piece during line-space feed of the 60 transfer material and work-piece, and for shifting the transfer material at intervals backward along the work-piece, a table connected to said platen carriage and comprising side bars formed of tubing, and metal 65 strips attached to said tubing both to reinforce the same and to serve as opposite guide-rails upon which said sub-carriage travels.

9. In a typewriting machine, a platen, a carriage therefor, a sub-carriage for holding transfer material between the plies of a work-piece during line-space feed of the 70 transfer material and work-piece, and for shifting the transfer material at intervals backward along the work-piece, a table connected to said platen carriage and comprising side bars formed of tubing, and metal strips attached to said tubing both to reinforce the same and to serve as opposite 75 guide-rails upon which said sub-carriage travels, said strips comprising flat metal bars arranged edge to edge, and the sub-carriage having guide-rolls to engage guide edges of the strips.

BENJAMIN P. FORTIN.
